UNITED STATES PATENT OFFICE.

FREDY ALLMENDINGER, OF NEW YORK, N. Y.

DESIGN FOR A LADY'S GIRDLE.

Application filed February 20, 1925. Serial No. 12,431. Term of patent 3½ years.

To all whom it may concern:

Be it known that I, FREDY ALLMENDINGER, a citizen of the Republic of Germany, residing at New York, in the county of New York and State of New York, have invented a new, original, and ornamental Design for Lady's Girdle, of which the following is a specification, reference being had to the accompanying drawing, forming part thereof.

In the drawing:

Fig. 1 is a plan view of a lady's girdle, showing my new design.

Fig. 2 is an edge view thereof.

I claim:

The ornamental design for a lady's girdle, as shown.

FREDY ALLMENDINGER.
